Filed June 21, 1962, Ser. No. 70,658

Term of patent 14 years

(Cl. D81—10)

FIG. 1.

FIG. 2.

FIG. 3.

FIGURE 1 is a bottom perspective view of a combined ceiling heater and electric light showing my new design; FIGURE 2 is a bottom plan thereof; and

FIGURE 3 is a partial cross-sectional view taken on a radius of the fixture.

The dominant features of my design reside in the portions shown in full lines.

I claim:

The ornamental design for a combined ceiling heater and electric light, as shown and described.
